UNITED STATES PATENT OFFICE

ALEXANDER S. SPIEGEL, OF CHICAGO, ILLINOIS, ASSIGNOR OF ONE-THIRD TO ROBERT GLENDINNING AND ONE-THIRD TO GABRIEL FELSENTHAL, BOTH OF CHICAGO, ILLINOIS.

HOLDER FOR PHOTOGRAPHS.

1,211,497.

Specification of Letters Patent. Patented Jan. 9, 1917.

Application filed February 24, 1916. Serial No. 80,232.

To all whom it may concern:

Be it known that I, ALEXANDER S. SPIEGEL, citizen of the United States, residing at Chicago, Illinois, have invented certain new and useful Improvements in Holders for Photographs, of which the following is a specification.

This invention is designed to provide a holder and mount for what are known as life motion photographs, that is where a picture is taken in three or more positions and gives the effect of motion when used in connection with a screen member.

The present invention is for the purpose of providing a holder or receptacle for these life motion photographs so that the photographer whether amateur or professional, will not be under the necessity of making up a holder or indeed of doing anything more than to take the life motion photograph, the holders being so cheaply made as to permit them to be bought anywhere so that the photographer need only take the pictures and then apply them to the holders which may be kept in stock.

The pictures are taken in at least three positions, and the moving effect is secured by utilizing a screen which is placed in such relation to the photograph that when motion is given the screen an illusion of motion in the photographed face or body follows, the screen being composed of lines which, moving over the photograph, conceals certain portions thereof and exposes other portions and thus gives the motion effect.

In carrying out my invention I use a blank of pasteboard with a double or turned back end, preferably the right hand end, having scorings so as to be movable after the manner of a hinge, the scored section carrying a flap which in turn carries the screen member made preferably of celluloid. The margins of the side walls of the blank are folded inwardly and a cover sheet with a central opening is applied to the cardboard base and the screen member covers the opening. There is a pocket left at the left hand end and after the photograph has been taken, preferably at one end of a card, it is inserted in the pocket of the holder, and after being adjusted to the screen, adhesive material is applied to hold it in place and afterward the projecting end of the card is cut off leaving the completed article.

In the accompanying drawing, Figure 1

shows a plan view of the blank forming the back part of the holder; Fig. 2 is a plan view of the cover portion of the holder; Fig. 3 is a perspective view of the blank of Fig. 1 partly folded; Fig. 4 shows the blank of Fig. 1 folded and with the screen member attached ready to receive the cover member; Fig. 5 is a longitudinal sectional view of the article complete; Fig. 6 is a view of the holder with the picture member in place.

In these drawings a blank *a* is utilized, as shown in Fig. 1, having its margins *b*, *b*, folded in as in Figs. 3 and 4, forming a guideway or space between. The right hand end of the blank, shown at *d*, has a double scoring so as to give a hinge action and this hinged end has a tab or flap *c*, scored at its point of connection with the part *d*. To the under side of this flap *c* the screen member *f* is pasted, as shown in Fig. 4, this having parallel opaque lines with intervening clear spaces. The photographic card containing the series of positions of the person whose picture has been taken is shown at *g* and has the picture at one end with a blank space shown at *g'*. A cover sheet *h* is fastened to the folded side strips *b*, and this cover sheet has a central opening *i* through which the screen shows. After the picture has been taken in three or more positions and developed in the usual way, the card which carries the picture is slipped into the open end of the holder and is properly pasted in relation to the screen, after which adhesive material is applied to the front and back of the card to hold it in place and thereafter the protruding end of the card is cut off, which completes the operation and gives a perfect article in which the photograph is sealed in place in proper position relative to the screen, and as the screen is carried by the flap, a hingelike or pivotal movement of the part *d* of said flap moves the screen in relation to the picture and gives the effect of motion.

What I claim is:

1. As a new article of manufacture, a holder consisting of a base having its margins on opposite sides thereof folded inwardly and upon the main portion of the base, a flap connected with the base at one end thereof, and a cover member having an opening and overlying the folded in margins of the base and attached thereto and leaving an opening at the end of the base opposite

that at which the flap is located, and between the said base and the cover member, said opening lying between the folded in margins and adapted to receive a card bearing the composite picture, and a screen located in the space between the cover and the base and between the margins of the base, and being connected with the flap, said flap being movable to displace the screen carried thereby in relation to the picture member when inserted into said space through said opening for producing a motion picture effect, substantially as described.

2. As a new article of manufacture, a holder for receiving and displaying composite picture cards to produce motion picture effects consisting of a base, a cover attached thereto, and spaced apart therefrom and

thereby providing a space for the reception of a composite picture card, a movable screen member in said space with means for reciprocating the same at one end of the holder, said holder having an open mouth at its end opposite that at which the screen operating means is located, said mouth communicating with the space between the base and the cover for the insertion of the composite picture card into said space, substantially as described.

In testimony whereof, I affix my signature 30 in presence of two witnesses.

ALEXANDER S. SPIEGEL.
